W. YANNAN,
Circular Saw Mill.

No 61,912.

Patented Feb. 5, 1867.

United States Patent Office.

WILLIAM YAMAN, OF CONNERSVILLE, INDIANA.

Letters Patent No. 61,912, dated February 5, 1867

IMPROVEMENT IN SAW-MILLS.

The Schedule referred to in these Letters Patent and making part of the same.

TO ALL WHOM IT MAY CONCERN:

Be it known that I, WILLIAM YAMAN, of Connersville, in the county of Fayette, and State of Indiana, have invented a new and improved Saw-Mill; and I do hereby declare that the following is a full, clear, and exact description thereof, reference being had to the accompanying drawings, forming part of this specification.

The nature of this invention consists in constructing a saw-mill in such a manner that flat or square pieces of timber may be sawed from the log, one at each movement of the log endways, back as well as forward, and a course of pieces each way from side to side, until the whole log is worked up.

To enable others skilled in the art to make and use my invention, I will proceed to describe its construction and operation.

Figure 1 is a longitudinal vertical sectional elevation from the line *xx*.

Figure 2 is a top plan view of the same.

Figure 3 is an end elevation, showing the manner by which the saws work in the log.

Letters of like name and kind refer to like parts in each of the figures.

A represents a rectangular frame, upon which are erected two posts or guides, *B B*, with a suitable cross-beam, *C*, framed to the top of the said posts or guides for their support. *D D'* are two cross-pieces, located one above the other, their respective ends being provided with gibbs, *a a a*, that fit and work up and down on the guides or posts *B B*. The said cross-pieces *D D'* form a kind of sash, being connected by two inclined pieces, *E E*, which stand on an inclination of about forty-five degrees, and firmly secured in this position to the said cross-pieces *D D'*. In the cross-piece *D* is a long slot or mortise, through which the lower ends of the inclined pieces project a short distance below, to which are secured the bearings *2 2* of the lower ends of the arbors of the saws. *A² A²* are two arbors, of common construction, that run in bearings, *2 2* and *3 3*, which are secured to the under side of the inclined pieces *E E*. *F F* are two circular saws, secured by any well-known means to the lower ends of the shafts or arbors *A² A²*, the surfaces of which stand precisely at right angles with each other, and cut in opposite directions, as will be more fully explained. *U* is a screw-shaft that passes down through the upper cross-piece *C* and connects with the upper cross-piece *D'* of the sash. *T* is a pulley, located upon the upper end of the said screw-shaft *U*, around which a belt passes, which extends and works around another pulley, *S*, located and secured to the upper end of a crank-shaft, *R*, for the purpose of elevating and lowering the saws, which are connected to the cross-pieces or sash *D D'*. *I* is a carriage, placed upon the frame *A*, the side pieces of the said frame *A* serving as ways or guides for the carriage *I*, at the ends of which are rabbets that fit and move upon the side pieces of the frame *A*. *H* is another carriage, that is placed and moves upon the carriage *I*, and upon which the log is placed that is designed to be cut up. *J* is a ratchet-bar, which works longitudinally in each end of the carriage *I* at *b b*, fig. 2. In the said ratchet-bar *J* works a pawl, *K*, the pawl *K* being attached to a crank-shaft, *L*, which runs longitudinally with the carriage *H*, in which it has bearings in each end of the said carriage *H*. *e e* are two short upright posts, which are secured one at each end of the frame *A*. In these upright posts, *e e*, are bearings in which are placed the cam-rod or shaft *M*, which is for the purpose of feeding the carriage *H* over, after the saws have passed through the log, for another cut; the carriage being prevented from having any lateral motion by the pawl *K* while the saws are cutting through the log. *P P* are pendent bars, which are secured one upon each side of the lower cross-piece *D*, upon the lower ends of which are pivoted near the centre, levers *O O*, one end of the said levers *O O* being connected by a pivot to spiral springs, *N N*, the said spiral springs *N N* being attached at one end to the lower cross-piece *D'* of the frame or sash. *Q Q* are arms or standards, attached to opposite corners of the carriage *I*, that engage the pivoted levers *O O* as the carriage passes back and forth, for the purpose of throwing off the piece of timber as it is cut from the log.

The operation of my invention is simple and perfect, it being driven by any of the well-known powers. The log is placed upon the carriage *H*, which is operated back and forth by a suitable feeding mechanism acting upon the carriage *I*, so as to feed the carriage *H* longitudinally back and forth, which is not shown, as I do not claim the means of feeding the log longitudinally to the saws as my invention. When the log has passed the saws, the carriage moving a little further, the hole in the ratchet *J* engages the curved portion of the shaft *M*, which operates the pawl *K* upon the shaft *L*, which is in the carriage *H* upon which the log is placed, moves

the log over laterally ready to cut another piece. As the carriage returns with the log, the shaft M, having a like curve at each end, feeds the log over for another cut, the saws cutting back and forth through the log, cutting a flat or square piece at each movement, as seen in fig. 3. When the log has been sawed from side to side, the shaft L is turned over with the pawl K, and likewise the curved or cam-shaft M is turned over, reversing the lateral feed motion, so that another tier is cut in the same manner as before, thus feeding and cutting alternately from side to side until the log is sawed up, so that no time is lost by any gigging or backward motion of the log. When the saws have passed through the log, the upright arm or standard Q engages the pivoted lever O, that is connected at one end to the spring N, when the said spring N is drawn back by the forward movement of the upright arm or standard until the carriage has passed a point that the pivoted lever O becomes disengaged or released, when the spring flies forward and strikes the end of the piece that has just been cut and drives it clear from the saws and the log. It will be observed that the teeth of the saws run in opposite directions, so that their action will be the same in the log as they cut alternately back and forth in the log, one saw cutting up out of the log while the other cuts into the log.

Having thus described my invention, what I claim as new, and desire to secure by Letters Patent, is—

1. I claim the carriages H and I, in connection with shaft L, pawl K, ratchet J, and curved shaft M, substantially as and for the purposes described.
2. I also claim the lever O, and upright standard Q, and pendant P, in combination with the spring N, substantially as described.
3. A self-setting carriage, operated by means of the curved shaft M, substantially as herein shown and described.
